UNITED STATES PATENT OFFICE.

CHARLES M. MARKHAM, OF CHICAGO, ILLINOIS.

FORM FOR CONCRETE CONSTRUCTION.

No. 903,996

Specification of Letters Patent.

Patented Nov. 17, 1908.

Application filed January 27, 1908. Serial No. 412,731.

To all whom it may concern:

Be it known that I, CHARLES M. MARKHAM, a citizen of the United States, residing at Chicago, county of Cook, and State of Illinois, have invented certain new and useful Improvements in Forms for Concrete Construction, of which the following is a specification.

My invention relates to forms for concrete construction.

In general practice, the forms used for concrete construction are made of wood and the forms for each column and beam are so constructed that the entire form must remain in place until the concrete is sufficiently set to remove them. The time the concrete must remain supported is set by law, and in some instances is as much as three weeks. It is evident therefore, that an immense quantity of lumber must be used in the construction of a building of any magnitude. Further a large percentage of the lumber used is broken in removing the form, unfitting it for further use, and large quantities of lumber are needed to properly brace the forms, especially the columns, to maintain any position while being filled with the concrete.

The object of my invention is to provide an improved form for concrete construction which will require the use of a much less quantity of lumber in the construction of a building than forms now employed.

A further object of my invention is to provide a knock down form for concrete construction, that is, a form which may be readily and quickly taken apart without danger of splitting or breaking the lumber of which it is composed.

Other objects will appear hereinafter.

With these objects in view my invention consists generally in a form for concrete construction comprising the form members proper in combination with a plurality of clamps or clamping members for holding the form together, which are readily detachable to dismember the form.

Further, my invention consists in a form for concrete construction especially for the beams, comprising the bottom supporting members and the side members, the latter being removable after the concrete is set in shape to be again used, and the former being permitted to remain to support the concrete until fully set.

My invention further consists in various

details of construction and arrangements of parts all as will be hereinafter fully described and particularly pointed out in the claims.

My invention will be more readily understood by reference to the accompanying drawings forming a part of this specification and in which,

Figure 1 is a vertical transverse section through a form for concrete construction embodying my invention in its preferred form, the supporting and clamping members being shown in elevation. Fig. 2 is a similar view illustrating the side members of the form partially removed, Fig. 3 is a side elevation of the form complete, Fig. 4 is a side elevation of the supporting members arranged beneath a concrete beam, the side members of the form being removed, Fig. 5 is a perspective view of a portion of a form for a square column, Fig. 6 is a side elevation thereof arranged for an octagonal column, Fig. 7 is a horizontal section through a form for an octagonal column, and Fig. 8 is a vertical section through the bottom of the column form.

Referring to the drawings, 1 indicates the bottom or weight supporting member of the form and 2—2 the side members.

It is necessary that the member, 1 remain under the beam until the concrete is sufficiently set to be self supporting, whereas the side members, 2 are necessary only until the concrete is set sufficiently to retain its shape.

In carrying out my invention, I provide means for detachably joining the members, 1 and 2 in order that the latter may be removed for further and immediate use as soon as the beam is sufficiently set, leaving the member, 1, and its support, beneath the beam until fully set and self supporting. To this end, I provide suitable clamps for holding the members, 2 in position until ready to remove them.

The bottom member, 1 is supported at intervals by the vertical posts, 3 formed of stout timber. Between the upper end of the posts, 3 and the member, 1 are interposed blocks, 4, the grain of which runs transversely to that of the member, 1. Secured to the upper end of the post, 3 is a horizontally disposed timber, 5, suitably braced by the angularly disposed members, 6. Pivoted upon the timber, or cross member, 5 are the members, 7 which constitute a pair

of levers to the upper ends of which are respectively secured the side members, 2, of the form. The members, 2 each comprise the side board, 2', and the members 2'', the latter of which constitute a small portion of the bottom of the form and are of the same thickness as the bottom member, 1. The lower ends of the members, 7 extend some distance below the cross member, 5 and between said lower ends is arranged a block, 8 spiked or otherwise secured to the post, 3 or the braces, 6. Wedges, 9 driven between said block and ends of the members, 7 force the side members, 2 firmly into position with the edges of the members, 2'' impinging firmly against the adjacent sides of the member, 1. In order to bring the members, 2'' in perfect horizontal alinement with the member, 1 the double wedges, 10 are driven between said members and the cross timber. The block, 4 is narrower than the bottom member, 1 and the wedges, 10 extend beneath both the members 2'' and the edges of the member, 1.

11 indicates the wooden beams for supporting the floor form, 12 and themselves supported by the vertical timbers, 13. The beams, 11 do not approach closely to the members, 2 in order that the latter may be removed when desired. To support the end of the beam adjacent to the members, 2, a block, 14 is interposed between said end and the timber, 5 and a wedge, 15, between the timber and the block affords means for jacking up the beam.

When the form is set up and tightened the concrete is filled in. As soon as the concrete in the beam form is sufficiently set to retain its shape, the side members, 2 may be removed and used again immediately. To remove the side members, the wedges 9 and 10 are removed as are also the blocks, 14. Then the bolts, 16 by which the members, 7 are pivotally secured to the cross member, 5 are removed. The side members including the levers, 7 may then be removed. This leaves the member, 1 and the posts, 3, beneath the concrete beam to support the same until it is fully set and self supporting.

It is obvious that with forms of this construction considerably less timber is necessary in constructing a building than with forms of the usual construction. Also, that there is no loss of timber from splitting or breaking in dismembering the forms.

The knock-down feature of the form is also applicable to those for the columns and I have illustrated the application of this feature in Figs. 5 to 8 inclusive. The column forms comprise the vertical members, 20, one member, 20 being provided for each side of the column, that is, four for a square column and eight for an octagonal column. These are held together by suitable clamps arranged in pairs as shown in the draw-

ings. The clamps comprise a pair of timbers, 21 arranged upon opposite sides of the column and connected by the bolts, 22, the ends of the timbers, 21 being provided with the notches or slots, 23 to receive the bolt. The pairs of clamps are arranged at intervals throughout the length of the form and the clamps of each pair are arranged alternately as shown in the drawings, that is, the members, 21 of one clamp are arranged at right angles to the corresponding members of the other clamp. When the octagonal form is employed triangular blocks, 24 are inserted between the corners of the clamp and the angularly disposed members, 20, the blocks being of sufficient length to be engaged by both clamps of the pair.

In the method now employed for constructing the columns large quantities of timber are necessary to brace the column forms. The upper end of the form is secured to the beam form and it is to prevent displacement of the lower end that the braces are employed. I obviate the necessity for using the braces by forming a center for the column form of concrete, which firmly holds the lower end of the form against displacement. This is illustrated in Fig. 8, 25 indicating the center. The center is formed in the proper location and of a shape corresponding to the cross section of a column. It is however, made a trifle smaller in diameter, that is about one half inch. The column form is placed above the center with its lower edge about the center. It is evident that if the center, 25 is firmly set, the bottom of the form cannot be displaced. When it is desired to remove the form the bolts, 22 are loosened and knocked out of the notches, the form then readily separating.

Having described my invention what I claim as new and desire to secure by Letters Patent is:

1. A beam form for concrete construction comprising a bottom member and suitable supports therefor, in combination with side members pivotally connected to said supports and wedges for clamping the same against said bottom member, substantially as described.

2. A beam form for concrete construction comprising the bottom member and suitable supports therefor, in combination with side members, levers fixedly connected to said side members and pivotally connected to said supports and wedges for operating said levers, to clamp said side members against said bottom member, substantially as described.

3. A beam form for concrete construction, comprising a bottom member and suitable supports therefor, in combination with a horizontally disposed member secured to each of said supports below said bottom

member, levers pivotally connected to said horizontal member, side members fixed to the upper ends of said levers, a block fixed to the support adjacent to the lower ends of 5 said levers and wedges arranged between said levers and said block, substantially as described.

4. A beam form for concrete construction comprising a bottom member and suitable 10 supports therefor in combination with a horizontally disposed member secured to each of said supports and below said bottom member, levers pivotally connected to said horizontal member, side members fixed to 15 the upper ends of said levers, horizontally disposed strips fixed to said levers and abutting the lower edges of said side members, said strips constituting portions of the bottom, means for operating said levers to plant 20 the sides in position, and means interposed

between said horizontal member and said bottom and bottom strips to bring the latter in alinement, substantially as described.

5. In a form for concrete construction a beam form comprising a bottom member, 25 supports for said member and side members pivotally and detachably connected thereto in combination with the floor form, beams supporting said form and means interposed between the ends of said beams and the 30 beam form supports for supporting the former when said side members are removed, substantially as described.

In testimony whereof I have signed my name to this specification in the presence of 35 two subscribing witnesses.

CHARLES M. MARKHAM.
